COMBINATION HEMMER AND STRIP GUIDE

Application filed December 16, 1927, Serial No. 240,534, and in Germany January 27, 1927.

The invention relates to new and useful improvements in a combination hemmer and strip guide, and more particularly a strip guide for directing an elastic strip which is secured within and to the article at the same time that the hem is stitched therein. An object of the invention is to provide a combined hemmer and elastic strip guide with means whereby the elastic strip guide may be shifted at the will of the operator so that the elastic strip may be directed across the path of one of the needles for fastening said elastic strip to the fabric, said shifting means including devices for frictionally holding said strip guide in set position, and stops for limiting the extent to which said guide may be shifted.

A further object of the invention is to provide a combined hemmer and strip guide of the above type wherein the strip guide may be shifted by means of a hand operated swinging lever, friction means being provided to hold the lever in any set position, and stops being provided to limit the extent of movement of the lever.

These and other objects will in part be obvious and will in part be hereinafter more fully disclosed.

In the drawings which show by way of illustration one embodiment of the invention;

Figure 1 is a front view of a combined hemmer and strip guide embodying the invention, and showing the same as attached to the work support of a sewing machine.

Fig. 2 is a plan view of the part shown in Fig. 1.

Fig. 3 is a sectional view on the line A, B of Fig. 5.

Fig. 4 is a sectional view on the line C, D of Fig. 5.

Fig. 5 is a plan view of a portion of the article stitched on the improved hemmer and strip guide.

The invention is directed to a combined hemmer and strip guide which forms a hem in a body fabric which is secured to the body fabric by lines of stitching, and which also directs an elastic strip between the lines of stitching and between the inturned hem and the body fabric so that said elastic strip is

placed in a pocket formed by the line of stitching joining the infolded portions which provide the hem on the body fabric.

The means for guiding the elastic strip is mounted on a slide which is capable of being moved in a direction at right angles to the line of feed for the purpose of shifting the strip guide, so that the strip may at the will of the operator be moved laterally across the path of one of the needles, and thus the needle caused to penetrate the elastic strip and secure said elastic by a line of stitching which is forming the hem in the body fabric. This plate which is shifted laterally is moved by means of a lever swinging in a vertical plane and readily accessible to the operator. The lever is provided with a slot which cooperates with a pin on the slide, and the shifting of the lever will move the slide endwise, and thus shift the elastic strip guide. A friction washer is provided for holding said lever in set positions, and stops are also provided for limiting the extent of movement of the lever.

Referring more in detail to the drawings, the hemmer for infolding the edge of the body garment is indicated at *a*, and the strip guide is indicated at *b*. This hemmer is of the usual character and is provided with a recess *c* properly shaped for infolding and underfolding the edge of the body fabric.

Referring to Figs. 3 and 4 of the drawings, the body fabric is indicated at *d*. This body fabric is infolded and underfolded as indicated at *e*. The body fabric thus folded is directed to the stitching mechanism which forms two parallel lines of stitching indicated at *w* and *w*. The elastic strip is indicated at *f*. It will be noted from Fig. 5 that the elastic strip at a certain portion of the hem fold lies between the lines of stitching *w* and *w*, and the strip is not penetrated by the needles as they form these lines of stitching. It will also be noted that at other portions in the article, the elastic strip has been shifted to one side relative to the hem in the body fabric so that the line of stitching *w* passes through the elastic strip at the same time that it forms and stitches the hem fold. The elastic strip as shown in the drawings lies between the infolded portion of the body

fabric and the body fabric. This elastic strip might be directed into a hem pocket if desired.

- 5 The hemmer is provided with a shank *g* which is secured to the work support *i* by suitable screws *h*, *h*. Mounted on the supporting base for the hemmer is a vertically extending bracket *k*. The fabric supporting plate of the hemmer overlies this bracket *k*.
 10 Located beneath the fabric supporting plate of the hemmer is the elastic strip guide *b*. Said elastic strip guide *b* extends in a direction at an inclination to the line of feed which is indicated by the arrow in Fig. 2. The needles are indicated in this figure at *v*, *v*. From the above it will be noted that the guide for the elastic strip will deliver said elastic strip in proper position to pass between the needles substantially at the delivery end of the hem
 15 folder.

The elastic strip guide *b* is formed integral with the plate *l*. This plate *l* is provided with slots *m*, *m* through which extend pins *n*, *n* carried by the bracket *k*. Also mounted on
 20 the bracket *k* is a shaft *o* which passes through an elongated slot in the plate *l*. On the outer end of said shaft is a hand lever *p*. Between the lever and the plate is a friction disk *s* which bears against a washer, pressing the same against the plate *l*, and thus it is that the lever will be frictionally held in set positions. The hub of the lever *p* is provided with a slot *q*. The plate *l* is provided with a pin *r* extending into the said slot *q*. When
 25 the hand lever is moved by the operator the pin *r* will be shifted through the connection thereof with the hand lever, and this will shift the plate *l* carrying the strip guide. The operator may at will move this hand lever in one direction or the other. When it is moved in the direction of the arrow in Fig. 1, the plate *l* will be moved to the right and the strip guide will be moved so as to draw the elastic strip across the path of the
 30 right hand needle *v*.

The plate *l* is provided with a recess in which is located a lug *t*. This lug is carried by an arm secured to the bracket *k*. The ends *u*, *u* of the recess serve as stops. The lug *t* is rigidly attached to the bracket, and when the plate is shifted in one direction, one of the stops will engage the lug and this will limit the swinging movement of the hand lever. When said plate is moved in the other direction, then the other stop will engage the lug, and this will limit the movement of the hand lever. The arm carrying the lug *t* may be adjusted on the bracket and the parts properly positioned so that the strip guide may be shifted just the desired distance, so as to cause said elastic strip to cross the path of the right hand needle. When so shifted the elastic strip will be moved nearer the edge of the fold forming the hem. Thus it is that the elastic strip while located between the lines

of stitching and housed thereby, is never moved so as to extend beyond the left hand line of stitching, as shown in Fig. 3, so that the edge of the strip would show.

Let us assume that the article being stitched is a circular article, and the line of stitching begins at the end *H* of the fabric which is being hemmed. The guide has been shifted so that the tape is stitched through by the right hand line of stitching *x*. After the end of the elastic strip has been well tacked to the garment, then the guide is shifted so that the tape will lie free between the lines of stitching. The tape at the time of being stitched in the pocket is stretched and when the circular portion of the garment has been finished and the other side edge or end thereof is reached, then the guide is again shifted so that the line of stitches *x* will pass through and tack the other end of the strip. The elastic strip may then be severed along the line *E*, *F* if desired, and whether it is severed or not when it is released from the machine, the strip returning to its normal position will gather the material, as indicated in Fig. 5 of the drawings.

It is obvious that minor changes in the details of construction may be made without departing from the spirit or scope of the invention as set forth in the appended claims.

What is claimed as new is:

1. The combination of a hemmer having a fabric supporting plate, means for infolding the edge portion of the fabric and directing the same to a stitch forming mechanism for forming independent lines of stitching, a strip guide independent of the hemmer and located beneath said fabric supporting plate and having its delivery end adjacent the delivery end of the folder and disposed so as to direct an elastic strip between the infolded portions and the body fabric and between the lines of stitching, means controlled by the operator at will for shifting said strip guide relative to the hemmer whereby the line of stitching adjacent the folded edge of the body fabric is caused to penetrate and secure said elastic strip to said body fabric, and yielding means for holding said strip guide in set position.

2. The combination of a hemmer adapted to direct a body fabric with its edge infolded to a stitch forming mechanism, a strip guide for directing an elastic strip between the infolded portions and the body fabric, a vertically arranged bracket carried by the hemmer, a vertically arranged plate supporting the strip guide, said plate having slots, pins carried by said bracket extending through said slots for supporting the plate, a vertically swinging lever adjacent the plate, said lever having a notch therein, and a pin on said plate engaging said notch whereby the swinging of the lever will shift the plate.

3. The combination of a hemmer adapted

to direct a body fabric with its edge infolded to a stitch forming mechanism, a strip guide for directing an elastic strip between the infolded portions and the body fabric, a vertically arranged bracket carried by the hemmer, a vertically arranged plate supporting the strip guide, said plate having slots, pins carried by said bracket extending through said slots for supporting the plate, a vertically swinging lever adjacent the plate, said lever having a notch therein, a pin on said plate engaging said notch whereby the swinging of the lever will shift the plate, and a spring washer between said lever and plate for holding the lever and plate in set position.

4. The combination of a hemmer adapted to direct a body fabric with its edge infolded to a stitch forming mechanism, a strip guide for directing an elastic strip between the infolded portions and the body fabric, a vertically arranged bracket carried by the hemmer, a vertically arranged plate supporting the strip guide, said plate having slots, pins carried by said bracket extending through said slots for supporting the plate, a vertically swinging lever adjacent the plate, said lever having a notch therein and a pin on said plate engaging said notch whereby the swinging of the lever will shift the plate, a spring washer between said lever and plate for holding the lever and plate in set position, a lug carried by said bracket, said plate having spaced stop shoulders cooperating with said lug for limiting the movement of the plate.

In testimony whereof, I affix my signature.
KARL MAIER.
